UNITED STATES PATENT OFFICE.

DAVID L. MILLSAP, OF POWERSVILLE, MISSOURI.

HARNESS.

Application filed March 15, 1924. Serial No. 699,453.

To all whom it may concern:

Be it known that I, DAVID L. MILLSAP, a citizen of the United States, residing at Powersville, in the county of Putnam and

5 State of Missouri, have invented certain new and useful Improvements in Harness; and I do declare the following to be a full, clear, and exact description of the invention, such as will enable others skilled in the art to 10 which it appertains to make and use the same, reference being had to the accompanying drawings, and to the figures of reference marked thereon, which form a part of this specification.

15 This invention relates to an animal harness and particularly to a harness for supporting a shield to be applied to swine. The physical characteristics of swine require special harness which is not adapted to be 20 used on other animals such as horses and sheep and harnesses for sheep and horses are not adapted for the physical characteristics of swine. This is due largely to the fact that the neck of the hog is approximately 25 the diameter of his girth, so the neck band must be approximately the size of the shoulder band and girth.

The shield is supported by the girth and due to the habits of swine, it is desirable 30 and practically necessary to make the shield of frost proof, flexible material, because a hog wallows in mud and marshy land, therefore if leather were used, the leather would curl when it became wet and the shield 35 would lose its efficiency. By making the shield of proper material which will not curl or be affected by frost or dampness, the objection to leather and the like will be eliminated.

40 The harness is shown as consisting of a plurality of bands of substantially equal diameters connected together by longitudinal connectors with a protective shield extending from one of the bands and the first two 45 bands are arranged in front and back of the shoulders with a breast strap connecting them, so that the animal cannot disconnect the harness by rubbing or rolling and the device is so constructed that liability of un- 50 authorized progeny will be entirely eliminated. The specific material recommended for the shield is German silver, because it is frost proof. A frost proof material as con-

templated in this case is one that is proof against frost, that is not affected by frost or 55 specifically a material on which the frost will not adhere.

In the drawings,

Fig. 1 is a perspective view of a boar hog to which my invention is applied. 60

Fig. 2 is a perspective view of the complete harness.

Fig. 3 is a detailed view of the top of the girth showing expandible tugs or connectors for the girth, and 65

Fig. 4 is two complementary adjustable side bars constituting connectors for the shoulder band and girth.

Referring now to the drawings by numerals of reference

1, 2, and 3 designate the three bands of harness consisting of the neck band, the shoulder band and the girth respectively. The neck band is adjustable through the medium of the buckles 4 and 5. The shoulder band is adjustable through the medium of the buckles 6 and 7. The girth is adjustable through the medium of buckles 8 and 9. The girth includes a loop 10 to which the side straps 11 and 12 are connected by the U-shaped members 13 and 14 having coil springs 15 and 16 thereon, the coil springs being contained in the loops 17 and 18 so that when the animal wallows or breathes, or when he feeds heavy, the girth 85 will expand or give, thus preventing binding, so I term the members 13 and 14 compensating members.

The neck band is connected to the shoulder band by two longitudinal shoulder straps 19 and 20 which are adjustable by providing buckles as shown, and the band 1 is also connected to the band 2 by an adjustable breast strap 21. The means for adjusting the straps will not be specifically described be- 90

cause they consist of the usual buckle connections. The band 2 is connected to the band 3 by a back trap 22 and the adjustable rigid side bar connections 23 and 24. The side bar connections each consist of two bars 100

25 and 26. (See Fig. 4). The bar 25 is fastened to the band 3 and the bar 26 is fastened to the band 2. The bars 25 and 26 have openings 27 and 28. The bar 25 has a 105

prong 29 which is adapted to engage one of the openings 28 and a bolt 30 may pass

through the aligning openings in the side bars as shown in Fig. 2 to fasten the bars in their adjusted positions.

The shield or apron 31 may extend from the band 3 and be secured in any suitable manner. I prefer to construct the shield of non-corrosive frost proof material such as German silver mesh, or the like for the reasons above enumerated. The method of applying the harness and its purposes will be clearly apparent by reference to the above description in connection with the accompanying drawings, and it will be obvious that the harness can be easily applied in a manner to prevent its becoming detached when the hog wallows or rubs against any object, as is his nature to do, and it will also be apparent that the rigid bars 25 and 26 constitute spaces for properly locating the girth and prevent its sliding lengthwise of the animal.

What I claim and desire to secure by Letters-Patent is:

1. A harness for swine comprising a neck band, a shoulder band and a girth, means for adjustably connecting the bands one to

the other and a depending, flexible shield of frost proof material suspended from the girth.

2. A harness for swine comprising a neck band, a shoulder band and a girth, means for adjustably connecting the bands one to the other and a depending, flexible shield suspended from the girth, the shield consisting of German silver mesh. 35

3. A harness for swine comprising a neck band, a shoulder band and a girth, means for connecting the various bands together including rigid side bars between the shoulder band and the girth and a flexible 40 shield suspended from the girth.

4. A harness for swine comprising a neck band, a shoulder band and a girth, means for connecting the various bands together including rigid side bars between the shoulder band and the girth and a flexible 45 shield suspended from the girth, the side bars being arranged in pairs with means for extensibly connecting them.

In testimony whereof I affix my signature.

DAVID L. MILLSAP.
